UNITED STATES PATENT OFFICE

2,526,957

THE SAVING DEVICE

Application June 4, 1946, Serial No. 674,178

4. Claimant (Cl. 286-16)

My improvement pertains to an oil-saving device of that class of attachment adapted to minimize waste of oil, lessen dangers of fires, clean oil and dirt from cables during the vertical movement thereof, and more explicitly has reference to an adjustable tensioning means resiliently embracing and yieldingly guiding an oil well cable.

The principal objects of the invention reside in providing an attachment which may be utilized upon oil well cables of any size, for wiping oil therefrom as the cable is reeled in or reciprocated in the oil well casing; which may be readily adjusted to give any desired wiping action upon the cable; and which is especially constructed to minimize wear upon the cable or the device.

Ancillary objects include the construction of a device in accordance with the preceding objects, which shall be compact, of light weight, easily assembled and disassembled for repairs and of economical construction.

These, together with various other objects which will become later apparent are attained by my device, whereof the drawings are to be regarded as illustrative only, and wherein:

Figure 1 is a vertical elevation showing the device in disassembled relation to a well casing.

Figure 2 is a horizontal plan view through the invention, being taken substantially upon the line 2—2 of Figure 1;

Figure 3 is a vertical sectional view taken substantially upon the line 3-3 of Figure 2;

Figure 4 is a view similar to Figure 3, taken at right angles thereto, but showing a modification; and

Figure 5 is a side elevational view of the cable guiding means shown in Figure 1.

Reference is first had to Figure 1, wherein 10 denotes generally my improved wiper, while 12 identifies an oil well steel cable adapted to reciprocate vertically in a conventional oil well casing 14 having a head or cap 16. The accessory 10 is formed by a housing 18 having a flanged and tapered lower extremity 20 adapted to be detachably secured in the well head 16 in known manner by fastening means 22.

At its upper end, the housing 18 supports a cable guide block 24 carrying a plurality of grooved cable embracing guide rollers 26, the block 24 being preferably integral with housing 18, although it may be separately formed where desired.

Turning now to Figure 2, it will be seen that housing 18 has an axial passageway receiving cable 12 loosely and slidably therein, and is

5 formed or has secured thereto a plurality of radially positioned, axially extending, ribs or bosses 28. As shown more clearly in section in Figure 3, the ribs 28 have radial guide slots or channels 30 extending completely therethrough into the axial passageway, the ribs terminating in rectangular flanges 32, and axial sleeves 34. Correspondingly contoured rectangular end plates 36 are detachably secured to the ends of the sleeves 34 in parallelism with flanges 32 by fastening means 38. It will be understood that any suitable fastening means may be employed in conformity with the invention.

Slidingly disposed radially in the channels 30
15 are wiping members 40 of any suitable resilient, deformable packing material. Members 40 may conveniently be of spongy rubber or porous, fibrous material and press against and in their entirety substantially encircle and embrace the cable 12, to wipe the oil therefrom and clean the same as the cable reciprocates through their combined grip. A follower plate 42 loosely fits in each slot 30 behind the packing 40 and serves to apply uniformly thereto the pressure of the
20 adjustment member 44, which may conveniently take the form of a headed bolt, screw-threaded through the end plate 36. Attention is now directed to Figure 4, wherein I have depicted a modified form of packing or stuffing box. In
25 this form, which is designed for a superior wiping and sealing action for heavier duty, a casing or radial rib 110 has one or more transverse or horizontal partitions 112 therein, thus forming vertically or axially spaced guide chambers 114 and 116. Each chamber slidingly receives a packing block 118, while a loosely fitting follower plate 120 is engaged by adjusting screws 122, threaded through the cover member 124, one such member being used for each rib. In this embodiment, one
30 horizontal set of packings may be of heavier, less yielding construction than the other set, if desired, in order to perform the additional function of guiding and dampening the vibrations of the reciprocating cable, and the various packings may be individually adjusted to any preferred pressure.

As will be evident, the individual packings 40 may be separately adjusted by bolts 44 to center the wire in the axial passageway, thus compensating for slight irregularities in either the mounting of the device upon the well head or the centering of the well cables in the casing. The cable guide 24 not only assists in centering the cable as it passes through the axial passageway but in some measure serves to absorb vibrations

therefrom during operation, preventing their being imparted to the soft packing surfaces. Finally, in addition to their packing and wiping functions, the members 40 constitute an effective resilient vibration dampening means for the cable 12.

It is with the intent of my invention to form the casing or portion thereof of vertically split construction with a view to obtaining easy attachment to or removal from operating well rigs.

It is to be understood that the drawings and specification are to be regarded as illustrative only of the principles of my invention, and that I do not limit myself thereto except as required by the following claims.

I claim as my invention:

1. A wiper for oil well lines, comprising a housing, an axial cable receiving passage therein, a plurality of radial diametrically opposed ribs thereon and extending axially the entire length of said housing, said ribs having upper and lower extremities terminating in common parallel horizontal planes, radial slots in said ribs communicating with said axial passage, partition means for each slot forming therewith a plurality of axially spaced guides, resilient cable wiping blocks slidably received within said spaced guides and extending the full length of said housing and engaging said cable throughout the full length of said axial passage, and means for adjustably urging said wiping means towards said axial passage.

2. The combination of claim 1, wherein said adjusting means comprises flanges upon each rib extending transversely from said ribs and perpendicular thereto, a plate abutting said ends of the ribs, fastening means securing said plate to

said flanges, a screw and follower adjustable through said plate for individually urging each of said wiping blocks against said cable.

3. The combination of claim 2, and a cable guide means supported solely by an end of said housing for axially aligning said cable with said axial passage, and outwardly tapered means for detachably clamping said housing to a well head.

4. A cable wiper, comprising a housing, an axial cable receiving passage therein, a plurality of ribs thereon and extending axially the entire length of said housing, said ribs having upper and lower extremities terminating in common parallel planes, slots in said ribs communicating with said axial passage, partition means for each slot forming therewith a plurality of axially spaced guides, cable wiping means slidably received within said spaced guides and engaging said cable substantially the full length of said axial passage, means for adjustably urging said wiping means towards said axial passage.

ELZY O. KUNKEL.
